(57) **CLAIM**

The ornamental design for a surface pattern applied to a container, as shown and described.

DESCRIPTION

FIG. 1 is a front perspective view of a first embodiment of a surface pattern applied to a container, shown on a flat surface;

FIG. 2 is a front elevation view thereof;

FIG. 3 is a top view thereof, the bottom view being a mirror image;

FIG. 4 is a right elevation view thereof;

FIG. 5 is a front elevation view of a second embodiment thereof, shown on a curved surface;

FIG. 6 is a front elevation view of a third embodiment thereof, shown on an undulating surface; and,

FIG. 7 is a top plan view of the second embodiment, the bottom view being a mirror image.

The broken lines shown illustrate environmental structure and form no part of the claimed design.

1 Claim, 6 Drawing Sheets
